(57) **CLAIM**

The ornamental design for a light reflector, as illustrated and described.

DESCRIPTION

FIG. 1 is a perspective view of the light reflector, according to the new and unique design;

FIG. 2 is a top view of the light reflector of FIG. 1;

FIG. 3 is a right side view of the light reflector of FIG. 1, the left side being a mirror image thereof;

FIG. 4 is a front view of the light reflector of FIG. 1;

FIG. 5 is a rear view of the light reflector of FIG. 1; and,

FIG. 6 is a bottom view of the light reflector of FIG. 1.
